(57) **CLAIM**

The ornamental design for a dust collecting box for a robotic vacuum cleaner, as shown and described.

DESCRIPTION

1. Dust collecting box for a robotic vacuum cleaner

1.1 : Front

1.2 : Back

1.3 : Left

1.4 : Right

1.5 : Top

1.6 : Bottom

1.7 : Perspective

Figs. 1.1-1.7 show a dust collecting box for a robotic vacuum cleaner that is used to store dust.

The broken lines in the drawings depict portions of the dust collecting box for a robotic vacuum cleaner that form no part of the claimed design.
